UNITED STATES PATENT OFFICE.

WILLIAM T. HUENING, OF CHICAGO, ILLINOIS, ASSIGNOR TO PAUL J. DAEMICKE COMPANY, OF CHICAGO, ILLINOIS, A CORPORATION OF ILLINOIS.

REFRIGERATOR DISPLAY CASE.

1,409,179.

Specification of Letters Patent. Patented Mar. 14, 1922.

Application filed February 24, 1919. Serial No. 278,776.

To all whom it may concern:

Be it known that I, WILLIAM T. HUENING, a citizen of the United States, and a resident of Chicago, in the county of Cook and State 5 of Illinois, have invented certain new and useful Improvements in Refrigerator Display Cases, of which the following is a description, reference being had to the accompanying drawings, which form a part of my 10 specification.

My invention relates to a display case or counter intended for displaying perishable articles of food, such as meat and the like, and at the same time enable them to be 15 refrigerated or maintained at suitable temperatures.

The invention contemplates a construction with one or more refrigerant holding chambers so arranged that ready access thereto, 20 as well as to the various parts of the display compartment or compartments, may be had; while at the same time proper circulation of air within the various compartments, as well as between the compartment or compartments and chamber or chambers will be provided and thus a substantially equal frigid 25 temperature throughout the case or counter maintained.

The invention also has for its object the 30 provision of a construction wherein the air is caused to pass in a direct path from the refrigerant holding chamber or chambers and therefore directly from the refrigerant medium, into the display compartment or 35 compartments; the construction contemplating means whereby the movement or flow of the refrigerated or chilled air may be more or less controlled.

The invention further contemplates a construction which is not only simple and efficient, but which will permit of its use merely as a display case when desired in sufficiently cold locations or exterior temperatures, and enable a proper circulation of fresh air 45 through the display compartment or compartments, without, however, permitting ingress of insects and the like.

My invention also has for its object the provision of a construction wherein the rising 50 warm air in the display compartment or compartments will not only be caused to flow into the refrigerant-holding chamber or chambers substantially at the highest point in the display compartment or compartments, but any condensation that may occur

will be caused to accumulate or adhere on an exposed chilled metallic surface adjacent the top of the display chamber or chambers and the point of communication with the refrigerant-holding chamber or chambers, 60 and thus not only assist in chilling the upper portion of the display compartment or compartments, but also prevent condensation or vapor forming on the glass or sight-openings of the case. 65

Another object of my invention is to provide a construction provided with ducts or flues for conveying cold air from the refrigerant-holding chambers into the lower part of the display compartment or compartments, as auxiliary means to the direct passages previously referred to, whereby cold air will be conducted as stated, especially in the event of the direct passages becoming obstructed in any manner. 70 75

The objects of my invention, as well as the advantages inherent in the construction, will be more fully comprehended from the following detailed description of the accompanying drawings, wherein:— 80

Figure 1 is a longitudinal vertical sectional view of my improved refrigerator display case.

Figure 2 is a detail view, in perspective, of the communicating port or opening and auxiliary air duct leading from the refrigerant-holding chamber into the display compartment. 85

Figure 3 is a vertical sectional view, taken on the line 3—3 of Figure 1, looking in the direction of the arrows. 90

Figure 4 is a longitudinal vertical sectional view of one end of the display case or counter illustrating a modified form.

Figure 5 is a detail view, in perspective, of the refrigerant-holding receptacle employed in the modified form shown in Figure 4. 95

In the particular exemplification of the invention, as disclosed in Figures 1 to 3, the display case, which is preferably of elongated rectangular construction in the nature of a display counter, comprises an outer wall 10 of any suitable material, such as wood, and provided with suitable supporting portions or blocks 11, preferably disposed about 100 all sides of the case. 12 represents an inner wall arranged in spaced relation with the outer wall 10; with the intervening space filled with suitable insulating material of cork and the like, as at 13; the inner wall or 105 110

shell 12 being formed of suitable material, such as wood, made to extend about the three sides of the refrigerant-holding chambers 14, 14, which, in the exemplification, are provided at both ends of the display case. The display case, at points intermediate of the refrigerant-holding chambers 14, at what may be termed the forward side of the case, consists of glass so as to provide a full or complete view of the interior of display compartment 15 and its contents.

The refrigerant-holding chambers are preferably formed with sloping bottoms, as at 16, preferably made of several thicknesses of wood; these bottoms being made to slope downwardly toward the display compartment; with the top surface of the bottom-boards preferably brought flush with the top surface of a bottom strip or sloping filler member 17 (which extends longitudinally toward the center of the display compartment from both refrigerant-holding chambers 14, 14); the filler strips sloping toward the center or drain-point of the counter or case. The space between the sloping bottoms 16 of the chambers 14 and the inner wall 12 of the case is filled in with suitable insulating material, such as cork and the like, as shown at 18, so that the refrigerant-holding chambers will also be thoroughly insulated at the bottoms as well as on the three sides disposed toward the outer sides of the display case. The space intermediate of the bottom strip 17 and the bottom of the inner wall 12 is also filled in with suitable insulating material, as at 19, thus in turn also providing a composite insulated bottom for the display compartment 15.

The inner walls of the refrigerant-holding chambers 14, as well as the bottom of the display compartment, are preferably lined with sheet metal, as at 20 and 21, so as to provide a non-absorbing, moisture shedding lining for said chambers and compartment. With the bottom or filler strip 17 of the display compartment preferably arranged at a slight inclination toward a point centrally intermediate of the refrigerant-holding chambers, a suitable drain is not only provided, but the display compartment is given slightly greater depth at the central point by having the bottom extend to a lower plane than that of the chambers 14, thereby enabling the chilled air to flow toward the center of the display compartment.

It is apparent from the construction shown and described that the chilled air, which naturally seeks a lower level or plane, will be induced to flow toward the center of the display compartment, instead of rising within the display compartment immediately adjacent the refrigerant-holding chambers.

The bottom of the display compartment at its central and lowest point is provided with a take-off pipe or drain 22 which ex-

tends through the bottom of the case while the upper end is shown provided with a nipple or flanged member 23 shown screwed onto the end of the pipe 22. The nipple 23 and drain tube 22 are situated in a depression formed in the bottom of the display compartment in order that a water-seal may be provided for the drain tube 22; the depression being metal lined and provided with an inverted cup member 24 which has scalloped or notched edges, as shown in Figure 1, in order to permit the water to pass through into the interior of the inverted cup member 24. The cup-member 24 rests on the horizontally disposed flange portion of nipple member 23; and is of a depth sufficient to have its up-turned bottom in spaced relation with the tip of nipple 23 and pipe 22 so as to permit free passage of the water. With this construction the water coming from the melting ice in the refrigerant-holding chambers 14 will fill the depression about cup member 24 and within the same until it reaches a level above the extended end of tube 22 and the vertically disposed portion of the nipple member 23; and with the notches or scallops of cup member 24 of such depth as not to extend above the plane occupied by the upper end of the drain-tube 22, it is evident that air will not be permitted to pass upward through tube 22 into the display compartment because of the water-level which will be maintained in the depression and which will seal the notches or scallops in cup-member 24.

The refrigerant-holding chambers 14 are preferably formed by employing a removable metallic receptacle 25, preferably of sheet metal as shown in Figure 1, formed so as to be in snug contact with the metallic lining 20; the receptacle 25 being made of the same configuration as the chamber 14 and provided with an opening 26 at the lowest point in the chamber disposed toward the display compartment. The opening 26 in the receptacle 25, which registers with a similar opening in the wall of the chamber, permits the cold air to pass directly into the display compartment at the immediate bottom thereof and therefore also from the coldest point in the receptacle. In order to prevent the passage of portions of the ice into the display compartment, I provide the passage 26, which extends the full width of the receptacle 25 and also of the refrigerant-holding chamber 14 as shown in Figure 3, with a suitable grating as at 27, which is held in place at the upper end by means of the metallic flange 28 secured to the side wall of the receptacle 25; while the lower ends of the grating or bars 27 are held in place by means of the upturned flange or lip 29, see Figure 1, formed on the bottom of the receptacle 25. With this construction, it is evident that the ice will be prevented from passing into the

display compartment, while at the same time the water, resulting from the melting ice, will be permitted to flow through the grating onto the downwardly sloping bottom of the display compartment and toward the drain at the center; the openings in the grating or between the bars or rods 27 being such, however, as to permit free egress of the chilled air from the chambers 14 into the compartment 15.

In order that the refrigerant-holding chamber may maintain as low a temperature as possible therein and also cause the cold air to pass out through the opening 26 at the bottom of the chambers, I prefer to provide the exposed metal side of each chamber disposed toward the display compartment or compartments with an insulated wall, as shown at 30, see Figure 1, composed of several

20 layers of cork-board or other suitable insulating material, encased in a metallic shell or housing 31, which is suitably secured to the metallic wall of the chamber 14. The insulated wall 30 extends throughout the entire 25 width of the refrigerant-holding chamber and throughout a greater portion of the wall in a vertical direction, namely from a point immediately above the opening 26 to a point slightly removed from the top of the refrigerant-holding chamber; the metallic shell or housing 31 being made with a sloping top so as to provide a shed of any condensation that may occur on the metallic wall above the housing 31. By having this insulating wall stop

35 short of the upper end of the refrigerant-holding chambers, a small portion of the chilled metallic wall of the refrigerant-holding chambers adjacent the top thereof and at the upper end of the display compartment

40 is left exposed in the display compartment as shown at the point 32 in Figure 1, while the major portion of the metallic wall is insulated and a relatively low temperature maintained in the chamber 14. The insulated

45 wall 30, or rather the shell or housing 31 thereof, provides suitable supports for the slatted shelves 33 and 34. In practice, no articles or food-holding trays are to be placed beneath shelf 33, as the space beneath

50 the shelf 33 is to be kept free and unobstructed for the free passage or flow of the cold air discharged from the chambers 14 through the openings 26 as previously described. The shelves 33 and 34 preferably

55 consist of suitable slats disposed transversely of the case so as to provide interstices or openings for the upward passage of the air; the shelves 33 and 34 being also supported in any suitable manner on what may be

60 termed the rear side or wall of the case; or any suitable means of support may be employed. The top wall of the case is shown extending slightly beyond the chambers 14 toward the display compartment as at 35,

65 where the top is shown kerfed to receive the

glass 36; the two plates being preferably held in spaced relation by means of a spacing strip 36^a, thereby providing a dead air space between the glass. The rear wall of the display case is formed of the wood partitions 10 and 12 spaced apart as previously described with insulating material therebetween as shown at the sides and bottom of the case and is provided at suitable intervals with properly hinged closure members or 70 doors 37, which are also of double thickness with insulating material between, similar to the walls of the case; the doors being arranged to have snug fit in the openings therefor so as to prevent passage of air; the 75 manner of hanging and supporting the doors 37 being of any suitable well known style.

The tops of the refrigerant holding chambers 14 are provided with heavily insulated lids or covers 38 which are formed so as to 80 extend into the openings or tops of the chambers in the manner shown; the immediate tops of the lids being shown disposed horizontally beyond the openings of the chambers so as to overlap the top of the case; the 85 margin or overlapping portions of the covers 38 being preferably provided with any suitable sealing medium, as for example rubber tubing partially embedded in and secured in shallow grooves as shown at 39.

At a point immediately beneath the bottom of the lids or covers 38, the ice-holding chambers are provided with air inlets or passages 40, whereby the air in the upper part of the display compartment is permitted to 90 pass into the refrigerant-holding chambers 14 above the refrigerating medium; the passages 40 being substantially at the uppermost point in the display compartment, namely at a point just beneath the glass top 36. 100 With this construction it is apparent that the rising warm air in the display compartment 15 will be caused to pass toward the ends of the display compartment and into the refrigerant-holding chambers 14, where it will 105 be chilled and caused to drop down through the refrigerating medium or about the ice and thence discharge through the opening 26, at the lowest point in each chamber 14, directly into the bottom of the display compartment 15. As a result of the action just described, it is evident that a complete circulation of air is set up within the case.

The shelves 33 and 34, in practice, are usually filled with article-holding trays, with 120 the result that a great portion of the chilled air will be induced to flow toward the center of the display compartment; being aided by the downwardly sloping bottom, as previously described. The chilled air, of course, 125 comes into contact, by means of the interstices in the shelves, with the bottoms of the platters or trays or food articles and chills the same in its passage toward the center of the compartment where the shelf 33 is pro- 130

vided with a large unobstructed opening 41, preferably disposed transversely of the shelf 33, which permits the air to rise. The opening 41 is at a point immediately above the 5 drain of the case and therefore above the lowest point in the compartment. In order to maintain this opening 41 unobstructed, and at the same time prevent articles falling therethrough, I provide a suitable wire 10 cage, as at 42, adapted to rest on the inner bottom of the case and extend through the openings 41 a distance somewhat above the level of the shelf 33, as shown in Figure 1. The wire cage 42 is so constructed as to permit 15 free upward flow of the air, while at the same time preventing the improper placing of platters or articles thereon whereby proper flow of the air would be hindered. It is apparent that when the shelf 33 has 20 been filled with platters or articles, the air discharged from the refrigerant-holding chambers will be forced to flow toward the center and caused to rise through the opening 41 and cage 42 toward the top of the 25 display compartment and cause the warm air to move toward the passages 40 of chambers 14, thereby inducing a current of air throughout the entire display compartment from a central point toward the ends thereof, namely through the openings 40 into the 30 chambers 14, thence down and out through openings 26 as previously described; while at the same time the cold water from the melting ice will also assist in cooling the 35 compartment. With this construction the entire display compartment 15 will be affected by the chilled air discharged from the refrigerant-holding chambers and a thorough circulation induced throughout the 40 display case. By leaving a small portion of the metallic walls of chambers 14 exposed adjacent the top of the display case as shown at 32, I have found in practice that any condensation that may occur in the compartment 45 15, will form or take place on this small exposed chilled metallic wall, by reason of the air currents, instead of on the glass, with the result that a clear vision will at all times be provided.

50 I prefer to provide the refrigerant-holding chambers 14 with auxiliary cold air ducts, shown in the nature of conduits 43 secured to the side wall of the receptacle 25, which is disposed toward the outer end of 55 the display case, and leading from a point near the top of the receptacle down along the side wall and the declining bottom thereof, and terminating at the opening 26 which communicates with the bottom 60 of the display compartment. Any suitable number of these ducts may be employed and they may be secured in any suitable manner or formed integral with the side wall of the receptacle; the ducts being formed with closed tops and open

lower ends; while the sides at right angles to the wall of the receptacle are provided with a suitable number of openings adjacent the top as at 44, for the ingress of air. These ducts not only assist in inducing a circulation of air from the upper part of the chambers 14 down into the lower part of the compartment 15 (as the ducts will be surrounded with ice), but they also ensure cold air being conveyed in the desired manner in 70 the event that the cracked ice should become packed about the grating 27 and thereby partially shut off the flow of air from the main portion of the receptacle 25. In practice, I prefer to have the grating 27 formed 80 so as to leave the outlet at the lower ends of the ducts 43 open, as shown more clearly in Figure 2.

In order to enable the temperature in the compartment 15 to be somewhat controlled, I 85 provide the dampers 45 which are pivotally secured at their upper ends beneath the insulated wall 30 and arranged to entirely or partially close off the opening 26 when desired; the dampers 45 being operable from 90 the display case exterior by any suitable lever or mechanism not shown.

In Figure 4 I show a modification of my improved display case, wherein the refrigerant-holding chamber 14, is constructed substantially similar to those shown in Figure 1, except that the refrigerator or ice-holding receptacle 46 is shown in the nature of a tilting bin provided on its bottom with one or more grooved cleats 47, see Figure 5, 100 adapted to rock on the strip or cleat 48 secured to the bottom of the chamber. In order to enable the tilting action of the receptacle the upper ends of the side walls are made arcuate, while the lowermost portion or tip disposed toward the display compartment is preferably truncated or cut away, as shown, and the grating 49 therefore is disposed at an inclination. The opening at the lower side of the receptacle 110 is, however, in close proximity to and disposed directly toward the opening in the bottom of the chamber 14 leading into the display compartment. This opening, like in the construction shown in Figure 1, is also 115 preferably provided with a damper 45. When this construction is employed, the end wall of the display case is preferably provided with a properly insulated and suitably hinged door or member 50 whereby access 120 to the receptacle may be had; the latter being provided with any suitable handle or grasp, as at 51. With this construction, the ice-holding receptacle 46 may be readily tilted outwardly when door 50 is opened for 125 the purpose of charging with cracked ice, or it may be easily removed from the chamber 14 and taken to any suitable place to be recharged or supplied with the ice and salt.

In Figure 4, I also illustrate a method 130

of arranging the cover or lid 38 for the top of the refrigerant-holding chamber in the event that the display case is employed during cold weather, that is in situations where 5 the outer temperature about the display case is sufficiently cool to permit the employment of the case without the use of a refrigerant medium. Where such use is contemplated, it is essential that proper circulation be 10 maintained in the case and at the same time prevent insects and the like entering the case or fixture. For occasions of this sort, the opening in the top of the refrigerant-holding chamber or chambers may be provided 15 with a wire netting or screen, as at 52, adapted to extend into the opening in the upper part of the chamber or chambers and rest on the off-set walls about the opening, as shown; while the upper part of the 20 wire netting or cage is made so as to receive the depending portion of the cover or lid as shown. With an opening thus provided at the uppermost point in the display case, it is evident that upon opening any 25 one or more of the doors in the lower part of the display compartment, namely at a point near the floor, extraneous air will be allowed to enter the bottom of the display compartment and the warmer air within the 30 case will pass upward therethrough and into the refrigerant-holding chambers through the various air passages or vents 40. If desired, one or more of the door-openings in the display compartment may be provided with screens and the doors of said compartment permitted to remain open.

As is evident from the preceding specification, one of the chief novel features of my invention exists in providing a solid, insulated bottom to the refrigerant-holding chamber or chambers;—which chambers are arranged immediately adjacent the ends of the display compartment;—and providing the lowest point of said chambers with an 45 opening or air passage directly into the lower part of the display compartment. With this arrangement the cold air will be discharged directly into the display compartment where its effect on the temperature of 50 the compartment will immediately occur. My invention overcomes the serious objections encountered with display cases as heretofore constructed, wherein an air space beneath the refrigerant-holding chamber or 55 receptacle has been provided, which space had to be chilled before any effect on the air or temperature in the display compartment was had. This has been found to be a serious objection because it resulted in an 60 improper refrigerated display compartment; and also required a greater quantity of ice being used, due to more frequent charging of the ice chambers. On the other hand, with my improved construction, the temperature of the display compartment can be

more readily maintained at the desired degree and the desired degree of temperature in the display compartment very promptly obtained after the refrigerant-holding chambers or receptacles have been 70 properly charged. The above mentioned feature, as well as the other features of novelty, are set forth in the appended claims.

What I claim is:—

1. A display-case provided with insulated 75 walls and consisting of a display compartment having a glass side and top and a water-sealed drain or outlet in the bottom, refrigerant-holding chambers, at the ends of said compartment, provided with downwardly sloping closed bottoms, the side walls of each chamber adjacent the lowest point in the bottom being provided with an opening leading directly into the bottom of said display compartment, air passages adjacent 80 the top of said compartment leading into the upper part of said chambers, and air-ducts in said chambers extending downwardly within the chambers and along the bottoms thereof and terminating at the 85 opening leading into the display compartment.

2. A refrigerator case of the character described, provided with a display compartment and refrigerant-holding chambers having insulated walls and bottoms, the side walls of the refrigerant-holding chambers adjacent the lowest part of the bottoms thereof being provided with openings leading directly into the bottom of the display 95 compartment, the inner walls of the refrigerant-holding chambers being made of metal, with the side walls disposed toward the display compartment being insulated from said openings to a point slightly removed from the tops thereof to provide an exposed chilled metallic wall in the upper part of the display compartment for the condensation of the moisture in the warm air, air-passages in said side walls of the 100 refrigerant-holding chambers immediately adjacent the tops of said chambers for conveying warm air from the display compartment into said chambers, and means, controllable from the case exterior, whereby the 105 openings at the bottoms of the chambers may be partially or entirely closed and the flow of cold air into the bottom of the display compartment regulated.

3. A refrigerator case of the character described, provided with an insulated bottom and walls and formed to provide a display compartment and refrigerant-holding chambers at opposite ends thereof, the inner bottoms of said chambers and compartment 110 sloping downwardly from opposite ends of the case toward the center of the display compartment, air-passages arranged at the immediate tops and bottoms in the walls between the chambers and said compartment, 115 120 125 130

- said walls being insulated intermediate of said passages at the top and bottom so as to provide an exposed chilled wall above said insulation, in the upper part of the display compartment, regulable means for regulating the size of the lower air-passages, the display compartment being provided with one or more shelves disposed from end to end of said compartment and arranged in spaced relation with the bottom thereof, the shelf nearest the bottom being provided with an enlarged opening at a point immediately above the lowest point of the inner bottom of the display compartment to permit upward passage of air.
4. A refrigerator case of the character described, provided with insulated walls and bottom and formed to provide a display compartment and a refrigerant-holding chamber at one side of the compartment, the refrigerant-holding chamber being provided at top and bottom with openings directly into said display compartment, metallic air-ducts in said chamber disposed downwardly and along the bottom thereof and communicating with the bottom of said compartment, said air-ducts also communicating with the upper end of said chamber to convey air therefrom.
5. In a refrigerator case of the character described, a display compartment and a refrigerant-holding chamber arranged at the end of the compartment, the refrigerant-holding chamber being formed with a solid bottom sloping downwardly toward the bottom of the display compartment, with an air-passage at the lowest point in said chamber leading into said compartment, a tilttable refrigerant-holding receptacle fulcrumed in said chamber adjacent the upper end of the sloping bottom of the receptacle, while the side adjacent the lowest end of said bottom is provided with an opening disposed toward and in close proximity to said air-passage, means whereby ice is prevented from passing through said opening and passage, the side wall of the receptacle, removed from the display compartment, being provided with air-ducts extending from top to bottom and to said opening at the opposite side, a closable opening in the side wall of said chamber through which access to said receptacle may be had and the latter tilted therethrough, and an air-passage between said compartment and said chamber at the immediate top thereof.

WILLIAM T. HUENING.
